Joseph Franklin

Letter Patent.

The schedule referred to in these Letters Patent and making part of ^{the} same containing a description in the words of the said Joseph Franklin himself of his Improvement in the Art of Pressing -

Be it known that I the said Joseph Franklin have invented, constructed and applied to use a new and useful improvement in the application of the wheel, pinion and crank or pulley to the screw in Pressing. The said prop containing said improvement and of a convenient size and power for pressing Cheese is specified in the words following viz: Construct a frame in the following manner, make two pieces for the post, fifteen inches long, two & a fourth inch thick & two & three fourths inches deep - exactly in the center of which, make a mortise five and one half inches long, and one inch wide; into these feet frame two posts two feet ten inches in length clear of the tenons, five & one half inches wide, & two & one fourths inches thick, in such a manner that they will incline forward three fourths of an inch in their whole length, where liquor is to be pressed; otherwise their, front will be at right angles with the post. Two and three fourths inches from the shoulder of the tenons, make two mortises parallel to each other through each of these posts three inches long, one inch wide leaving a space of one and three fourths inches, between them, also within three inches of the upper - end of the post, make two similar mortises, then on the inside of said post two inches below the upper mortises, and exactly under the same, make two mortises, of one inch square and one inch deep, also on the inside of the post, make a groove one inch wide and three fourths inches deep, extending from the lower edge of the small mortises, to within one inch of the upper edge of the first described mortises, and equally in the center of the post.

These posts are connected by three pieces of timber, two of which called beams are five & half inches wide, three inches thick, and fifteen inches long from shoulder to shoulder with tenons corresponding with the aforesaid mortises of a sufficient length to admit of a key on the outside of the post; the other

8/3/1831

6741X

of the same length and width of the beams, one inch thick with tenons corresponding with the small mortises in the posts. — On the front side of each post in the centre thereof and within six inches of the upper end, is made a mortise three inches long, one inch wide and two inches deep; into these mortises, frame two pieces, five & half inches wide, five inches long and two & one fourth inches thick, by tenons projecting from the centre of the under edges of said pieces, and corresponding with said mortises, within one inch of the outer end of each of these pieces, and within three fourths of an inch of each edge, make a mortise through the same of one inch square — let the ends of these two pieces be connected by a piece fifteen inches in length from shoulder to shoulder, five & half inches wide, two inches thick, with two tenons at each end corresponding with the mortises in the pieces last described so as the front side of said pieces may exactly correspond with the end of the aforesaid piece. — Construct a platform fifteen inches wide eighteen inches long, and one inch thick. this fasten on the upper side of the lower beams of the porch, so as to project three inches more to the front side than to the rear. — On the upper side of said platform, cut a circular niche, whose centre should be exactly in the centre of the porch, and whose diameter is fourteen inches, diverting from the regular periphery of said circle so as to conduct the liquid to the front side of the porch; construct a screw of wrought-iron eleven inches long, let nine inches of the same be turned, to receive eighty of an inch thick. — On this part cut a thread eight inches long, one inch round and smooth, the next inch on the same to be square, for the purpose of admitting a cog wheel, the balance projecting above said wheel, must be turned nearly to a point to prevent friction in passing, which point is placed against a step or plate of iron or steel fastened in the centre of the lower side of the ^{upper} beam of the porch. —

For the purpose of a collar to support the screw, take an iron plate of two & half inches square, one eighth inch thick; in the centre of which is a hole sufficiently large to admit the neck of the screw, this plate is fastened on the upper side of the small piece below the upper beam of the porch, the hole of the collar, to correspond with a hole through the centre of said piece to admit the screw. — To this screw is fastened as follows by means of a nut fastened into the upper side of the platform, fifteen inches long

from shoulder to shoulder, eight inches high, and three inches thick, with knobs at each end, corresponding with the grooves on the inside of the posts. —

Through the center of the following corresponding with the center of the post, bore a hole of sufficient size to admit the screw to pass freely. — On the square part of the screw, fasten firmly a cast iron cog wheel, twelve inches in diameter, with the cog on the upper side for the purpose of turning it, with a vertical spur wheel or pinion: This vertical wheel is six inches in diameter, and of cast iron with a square hole in the centre, for the purpose of admitting a wrought iron gadgeon, this gadgeon is eight and a half inches long, one end is turned and works in a box placed upon the top of the upper band near the edge, then from that end measure five & half inches towards the other and there turn another part for the purpose of working in a box, fastened in the centre of the upper side of the piece extending across the front side of the post. — This gadgeon is placed horizontally in such a manner as to admit the vertical wheel which is fastened firmly upon it to wash regularly into the horizontal wheel on the head of the screw, two inches of the square part of this gadgeon will project over the front side of the post, for the purpose of admitting a pulley, by which the post is moved; this pulley is thirteen inches in diameter, and so turned that it will admit of a cord to pass round it, to which a weight is suspended when it is required to continue the post.

Into the front side of this pulley and near the edge of the same put a handle, projecting three inches from the pulley. Application.

The method of using this post is simply to place the article to be forged upon the platform, then by turning the pulley with the hand the screw is caused to turn, by which means the following is forced to slide down the groove on the inside of the posts.

If after turning with the hand it is required to continue the post, suspend a weight to the pulley by a cord. — The same principle will hold good with any number of screws, by connecting them with cog wheels at the head. I would however observe that the proportions may be varied according to the nature of the article to be forged and the quantity of power required. — The foregoing specification relates to a machine sufficiently powerful for the forging of choice, but that of a machine sufficiently large for forging iron let the horizontal wheel be enlarged to pass over a post of required size the screw in proportion.
